US00D782834S

(12) **United States Design Patent** (10) **Patent No.:** **US D782,834 S**
(45) **Date of Patent:** **** Apr. 4, 2017**

(54) **ELECTRIC SUPPORT FOR HEADREST**

(71) Applicant: **Dongguan Weihong Hardware and Plastic Products Co., Ltd.**, Dongguan (CN)

(72) Inventor: **Wei Lu**, Dongguan (CN)

(73) Assignee: **DONGGUAN WEIHONG HARDWARE AND PLASTIC PRODUCTS CO., LTD.**, Dongguan (CN)

(**) Term: **15 Years**

(21) Appl. No.: **29/548,880**

(22) Filed: **Dec. 17, 2015**

(30) **Foreign Application Priority Data**

Sep. 8, 2015 (CN) 2015 3 0344199.5

(57) **CLAIM**

The ornamental design for an electric support for headrest, as shown and described.

DESCRIPTION

FIG. 1 is a front elevational view of an electric support for headrest showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan thereof;

FIG. 7 is a first perspective view thereof;

FIG. 8 is a second perspective view thereof; and,

FIG. 9 is a perspective view showing another position thereof to be used.

1 Claim, 7 Drawing Sheets
